UNITED STATES PATENT OFFICE.

FRED R. STILL, OF DETROIT, MICHIGAN, ASSIGNOR TO AMERICAN BLOWER COMPANY, OF DETROIT, MICHIGAN, A CORPORATION OF MICHIGAN.

COKE-QUENCHING APPARATUS.

SPECIFICATION forming part of Letters Patent No. 790,326, dated May 23, 1905.

Application filed July 11, 1904. Serial No. 216,134.

To all whom it may concern:

Be it known that I, FRED R. STILL, a citizen of the United States, residing at Detroit, in the county of Wayne and State of Michigan, have invented certain new and useful improvements in Coke-Quenching Apparatus, of which the following is a specification, reference being had therein to the accompanying drawings.

- 10 The invention relates to a ventilating apparatus especially designed for use in gas-houses; and it consists in the peculiar and simple construction of the apparatus, as will be fully hereinafter described and illustrated.
- 15 In the drawings, Figure 1 is a view of the interior of a gas-house, illustrating the ordinary retorts for the bituminous coal and showing in front elevation my improved ventilating apparatus. Fig. 2 is a sectional view showing a top plan view of a portion of the apparatus. Fig. 3 is an enlarged sectional view. Fig. 4 is an enlarged view of a part of the apparatus, showing the same in front elevation. Fig. 5 is a modification, 25 and Fig. 6 is an enlarged sectional view.

In the drawings thus briefly described the reference-letter A represents one of several vertical series of retorts of ordinary construction, the arrangement being the customary one in gas-houses. Beneath these retorts is the usual flooring B, provided with openings C, arranged one beneath each vertical series of retorts, as indicated.

Beneath the flooring and extending longitudinally of the series of retorts is the receptacle C', secured in place by straps D in the form of angle-irons connected at their extremities to the wall E and to the beams F of the flooring. The beams, as in usual floor construction, are spaced some distance apart, and the front wall a of the receptacle extends upwardly between the beams and is suitably attached to the flooring proper, as plainly shown in Fig. 3.

45 At one end the horizontally-extending receptacle is closed, as at b, while the opposite end terminates in an air-conduit E', leading outside of the building. Means in the form

of a fan F' is employed for creating a draft within the receptacle, the fan-casing, as shown, having communication with the air-duit; but any other means for inducing a draft may be employed—as, for instance, the connection of the receptacle with the usual stack for the building.

55 Formed in the front wall a of the receptacle C' are a series of discharge-openings c, preferably one for each inlet-opening C, and the bottom wall d of the receptacle is preferably inclined, as shown in Fig. 3, in the direction of the discharge-outlets, so that the receptacle contents may be readily withdrawn when desired.

60 Doors G are employed as closures for the discharge-outlets c, and a receptacle, preferably in the form of a car H, is mounted for longitudinal travel beneath the doors controlling the openings, as shown.

65 After the gases from the bituminous coal in the retorts have been driven off the coke is withdrawn from the retorts and dumped within the longitudinally-extending receptacle, where it is sprayed by suitable apparatus inserted within the door-controlled discharge-openings and subsequently removed from the 70 receptacle.

75 Preferably the inlet-openings C are provided with doors g, as illustrated in Figs. 1, 2, and 3, and under normal conditions these doors, together with the doors G, controlling 80 the discharge-outlets c, are closed. In emptying one or a series of retorts the door of the corresponding inlet-opening in the receptacle C' is opened and the coke dumped therein. The spraying is then effected, usually by inserting the nozzle of a hose within the door-controlled opening, and subsequently the coke is discharged from the receptacle into the car. The gases and vapors given off by the sprayed coke are carried by the draft created by the fan through the air-conduit and eventually discharged outside of the building.

85 In a modified form of apparatus, as illustrated in Fig. 5, I have shown a longitudinally-extending receptacle J, built in a similar manner to the one previously described,

but having but one discharge-outlet at its end. The receptacle extends to the wall K of the building and communicates with an opening L in said wall of sufficient size to permit of the extension therethrough of the conveyer M. The conveyer referred to is adapted to travel on suitable tracks O, Fig. 6, and may be operated in any suitable manner—as for instance, by an engine or motor P, also within the receptacle at the end opposite the discharge-outlet. A similar draft-conduit Q is employed with this type of receptacle, and the latter has the usual inlet-openings R, corresponding in number to the several series of retorts.

In operation the coke is dumped from the retorts through the inlet-openings in the receptacle onto the conveyer, which is traveling continuously, and is discharged outside of the building, as indicated, from whence it may be carted away to be shipped or stored. The spraying in this instance is effected by inserting the hose-nozzle through the inlet-openings or in any other convenient way. All of the gases and smoke arising from the coke is discharged, by means of the air-conduit, outside of the building, and the gas-house is properly ventilated.

What I claim as my invention is—

1. In an apparatus of the character described, the combination of a substantially horizontally extending receptacle having formed lengthwise therein a series of fill-openings and a corresponding number of discharge-outlets, and a draft-conduit communicating with the receptacle and adapted to remove the gases and vapors produced by the receptacle contents.

2. In an apparatus of the character described, the combination of a substantially horizontally extending receptacle having formed lengthwise therein a series of fill-openings and a corresponding number of discharge-outlets, closures for the outlets, and a draft-conduit communicating with the receptacle and adapted to remove the gases and vapors produced by the receptacle contents.

3. In an apparatus of the character described, the combination with a horizontally-extending receptacle having a series of inlet-openings in its top, and a corresponding number of discharge-outlets, the wall of the receptacle being inclined toward said outlets, closures for the outlets, and a draft-duct communicating with the receptacle.

4. In an apparatus of the character de-

scribed, the combination with a horizontally-extending receptacle having a series of inlet-openings in its top, and a corresponding number of discharge-outlets formed in one side, the receptacle-bottom being inclined toward said outlets, closures for the discharge-openings, closures for the inlets, and a draft-conduit communicating with the receptacle.

5. In an apparatus of the character described, the combination with a series of retorts, of a horizontally-extending receptacle in operative relation thereto having formed in its top a plurality of fill-openings corresponding in number to the retorts, and a corresponding number of discharge-outlets, closures for the inlets and outlets, and a draft-conduit communicating with the receptacle.

6. In an apparatus of the character described, the combination with a number of vertical series of ovens or retorts, of a receptacle extending longitudinally thereof, having a corresponding series of inlets below the retorts, and a number of discharge-outlets, independently-operable closures for the outlets, and a draft-conduit communicating with the receptacle.

7. In an apparatus of the character described, the combination with a retort, of a receptacle therebeneath having an inlet-opening and a discharge-outlet, a closure for the outlet and a draft-conduit communicating with said receptacle, at its side.

8. In an apparatus of the character described, the combination with a series of ovens or retorts, of a receptacle extending longitudinally of and below the retorts, said receptacle having a plurality of inlet-openings to receive the retort contents and a discharge-opening, closures for said inlet and discharge openings, and a draft-conduit communicating with said receptacle, at one side thereof.

9. In an apparatus of the character described, the combination with a horizontally-extending receptacle having an inlet-opening at its top, a discharge-outlet, the wall of the receptacle being inclined toward said outlet, a closure for the outlet, and a draft-duct communicating with the receptacle.

In testimony whereof I affix my signature in presence of two witnesses.

FRED R. STILL.
